DESIGN FOR AN ENSEMBLE DRESS

Samuel Weill, New York, N. Y.

Application December 21, 1938, Serial No. 81,928

Term of patent 3½ years

To all whom it may concern:

Be it known that I, Samuel Weill, a citizen of the United States and residing in Manhattan, in the city, county, and State of New York, have invented a new, original, and ornamental Design for an Ensemble Dress, of which the following is a specification, reference being had to the accompanying drawing, forming part thereof, wherein

Fig. 1 is a front view of an ensemble dress with a jacket showing my new design.

Fig. 2 is a rear view thereof.

Fig. 3 is a front view of an ensemble dress without the jacket showing my new design.

Fig. 4 is a rear view of Fig. 3.

The scarf is permanently attached.

The characteristic feature of my design resides in the combination on the ensemble disclosed of the specific redingote having puffed stitched embroidery on either side of the front opening and on the neck line and sleeves as shown, in association with four flap pockets below the belt line, the embroidered trim of the redingote being repeated around the neck line of the dress section.

I claim:

The ornamental design for an ensemble dress, substantially as shown and described.

SAMUEL WEILL.
